UNITED STATES PATENT OFFICE

167,062

TYPE CLEANING DEVICE FOR TYPEWRITERS

Paul R. Touney, Toledo, Ohio

Application June 12, 1951, Serial No. 15,506

Term of patent 14 years

(Cl. D74—1)

To all whom it may concern:

Be it known that I, Paul R. Touney, a citizen of the United States, and resident of Toledo, county of Lucas, and State of Ohio, have invented a new, original, and ornamental Design for a Type Cleaning Device for Typewriters, of which the following is a specification, reference being had to the accompanying drawings, forming a part thereof.

In the drawings, Fig. 1 is a perspective view of a type cleaning device for typewriter, showing my new design; Fig. 2 is a top view thereof; Fig. 3 is an end view and Fig. 4 is a side view of the device.

The dominant features of the design reside in the portions shown in full line.

I claim:

The ornamental design for a type cleaning device for typewriters, substantially as shown and described.

PAUL R. TOUNEY.
